STRAND HANDLING APPARATUS

Waldemar C. Ewaldson, Millington, N. J., assignor
to Western Electric Company, Incorporated,
New York, N. Y., a corporation of New York

Application August 14, 1941, Serial No. 406,855

8 Claims. (Cl. 242—45)

This invention relates to strand handling apparatus, and more particularly to apparatus for controlling the longitudinal speed of electrical cable while in process of manufacture.

In the manufacture of cable, especially of the somewhat complexly organized multi-conductor cables employed in telephony, a plurality of constituent strands may be rotated to intertwist the strands while the intertwined strands are propelled longitudinally. The pitch, or degree of twist, of the cable thus produced depends upon the ratio between the rotary speed of twisting and the linear speed of advance of the cable. The cable is usually advanced by being wound up on a take-up reel or drum, with or without the aid of some form of capstan; or, if the cable is to undergo further treatment, may be advanced by a capstan. Being thus pulled along against resistance offered by the twisting means and by tensioning devices applied to the supply reels or to the strands being supplied, tension is maintained in the cable by the advancing or pulling means. If the resistance rises or drops for any reason, the tension will rise or drop, and the pulling means will pull the cable along too slowly or too rapidly. Hence the speed of advance of the cable tends to vary more or less inversely as the tension; and uniformity of pitch of the cable depends upon uniformity of tension.

An object of the present invention is to provide an improved apparatus actuatable by and in response to a change in tension in an advancing cable or other strand to correspondingly alter the speed of advance, which apparatus shall be sensitive and quick to respond, shall be effective in proportion to the magnitude and swiftness of the change in tension, and shall operate to control over compensation and consequent hunting.

With the above and other objects in view, the invention may be embodied in a strand handling apparatus having means to advance a strand longitudinally and means adjustable to control the speed of advance of the strand, means responsive to variations of tension in the strand to adjust the speed control means, and means to cause the responsive means to actuate the speed control means intermittently.

Other objects and features of the invention will appear from the following detailed description of one embodiment thereof taken in connection with the accompanying drawings in which the same reference numerals are applied to identical parts in the several figures and in which

Fig. 1 is a view in front elevation of an ap-

paratus constructed in accordance with the invention:

Fig. 2 is a similar view of the apparatus with added elements;

Fig. 3 is a plan view of the showing of Fig. 2;

Fig. 4 is a wiring diagram of the electrical control circuit;

Fig. 5 is an enlarged detail view of a portion of the switch supporting and actuating levers;

10 Fig. 6 is a section on the line 6—6 of Fig. 5;

Fig. 7 is a detached diagrammatic view of the variable speed transmission;

Fig. 8 is an enlarged detail view on the line 8—8 of Fig. 7; and

15 Fig. 9 is a diagrammatic view of the apparatus of Fig. 2 showing one form of driving means for the strand.

As herein disclosed, the invention is illustrated as applied in connection with the spooling or taking up of a cable or other like strand, only so much of the related apparatus being shown as is necessary for an understanding of the invention.

Let it be assumed that a cable 19 is being advanced longitudinally of itself from left to right 20 in Figs. 1 and 2 by being wound upon a spool, reel, drum or other analogous rotatable take-up means or by being drawn along by a capstan 18 or other advancing means, at the right, against some resistance afforded by means at the left 30 (not shown), e. g. cable forming means of some kind. Let it be further assumed that the cable advancing means 18 be driven by mechanical or other interconnections, e. g. shafts 17 and gears 16, from the output shaft 42 of a suitable variable speed transmission device such as that generally indicated at 40. The particular device 40 here shown is that commercially known as a Reeves variable speed transmission and is described in detail hereinafter, but any analogous 35 suitable device may be used instead.

The weight of the cable, which is unsupported during its passage through the distance shown, causes it to hang in a downwardly convex catenary curve whose depth will depend on the tension 45 existent in the cable. Should the tension diminish, the cable will sag, deepening the curve; and should the tension increase, the curve will become shallower. This fact is the primary factor in causing the cable to control the tension in 50 the cable by means of the apparatus embodying the invention.

A horizontal lever 20, pivotably mounted on a hollow, transverse, horizontal shaft 21 supported in a pedestal 26, carries a sheave or roller 22, 55 which rides on the downwardly curved free hang-

ing portion of the cable, preferably near the bottom thereof, and is counterpoised by a weight 23 to follow changes in sag of the cable sensitively without causing any undue additional strain on the cable.

Now consider particularly Fig. 1. A vertical plate-like support 30 is rigidly mounted on the shaft 21 to turn with the lever 20 and carries two electric switches 35 and 36, one on each arm. Actuating levers 37 and 38 are mounted on the plate 30 to operate the switches 35 and 36 respectively and are confined in their motion between fixed stop pins under them and adjustable stop screws above them as shown. A second horizontal plate-like support or lever 130 is mounted on the pedestal 26 on a pivot 131 vertically under the shaft 21 and spaced therefrom. The support 130 is rotatable on its pivot but against frictional resistance. On the upper edges of the horizontal arms of the support 130 and respectively under the ends of the levers 37 and 38 are mechanical contact shoes 137 and 138 to coat with the lower edges of the outer ends of the levers 37 and 38 respectively as hereinafter described. Pawls 27 and 28 suitably mounted on depending extensions of the plate 30, are arranged to just pass the respective ends of the lever 130 when the parts are in the normal position shown in Fig. 1. The two switches 35 and 36 are connected into the power supply circuit of the motor 52 (Fig. 4) which drives the control shaft 43 (Fig. 7) of the variable speed means 40. The switches are so connected that when switch 35 is closed, the motor 52 drives the shaft 43 to lessen the speed of the output shaft 42, while closing switch 36 causes the speed of shaft 42 to increase. The wiring diagram in Fig. 4, showing the interconnections of the switches 35 and 36 in the power supply to the motor 52, is believed to be self-explanatory and not to need detailed description.

To describe the operation of the arrangement of Fig. 1, let it be assumed that the cable 19 is being advanced from left to right with its speed of advance and hence its tension under control of the device 40. As shown, conditions are presumed to be normal, i. e the tension in the cable is that desired, the lever 20 and the support 30 and the support 130 are all horizontal, and both switches 35 and 36 are open. The motor 52 is therefore idle and the device 40 is running with a fixed speed ratio of its input and output shafts. Let the resistance to advance of the cable begin to diminish for any reason. The tension in the cable is lessened and the catenary on which the member 22 is supported sags. The lever 20 turns clockwise, carrying the shaft 21 and the plate 30 with it. The lever 38 comes down on the member 138 and is moved on the plate 30 to close the switch 36. The motor 52 starts and drives the shaft 43 to cause the speed of the output shaft 42 to increase and thus increase the speed of the advance of the cable and hence the tension in the cable. Meanwhile the lever 20 continues to turn. The pawl 28 moves below and under the corresponding end of the lever 130 while the pawl 27 moves above and away. The pressure of the lever 38 on the shoe 138 turns the lever 130. Since the pivot of 130 is below the pivot of 30, the contact edge of 38 slides inwardly along the top face of the shoe 138. The top face of each shoe 137 and 138 is transversely notched or serrated in the manner best shown in Fig. 5. When the contact edge of 38 falls into the first of these serrations, lever 38 allows the switch 36 to open and the motor 52 stops.

If, during the brief interval of time thus consumed, the tension has been increased again to normal, the sag in the catenary is stopped and taken up. If not, the contact edge of 38 slips 5 up on the next serration of 138, closes the switch 36 again, and restarts the motor 52 to effect another increment of speed at the shaft 42. In effect the arrangement acting thus causes a small increment of speed at the shaft 42, pauses for a brief interval, effects another increment, pauses again as if to see if the total correction is sufficient, and so on until the sag of the catenary begins to diminish. When the sag begins to diminish, the lever 20 moves counterclockwise, carrying the plate 30 with it. The lever 38 is lifted clear of the shoe 138. A moment later the pawl 28 engages under the lever 130; and the whole returns to the status of Fig. 1. In the drawing the gap between the levers 37 and 38 and the shoes 137 and 138 respectively is exaggerated for clarity. In practise it will preferably be barely sufficient to enable the operation as described with a minimum time lapse between the start of motion of the lever 20 and the responsive start of actuation of the motor 52.

It is believed that the operation in case of an undesired increase in tension in the cable with consequent lifting of the catenary is too obvious after the above to require detailed explanation.

As before stated, the cable advancing means (not shown) is assumed to be driven from the output shaft 42 of the device 40, while the input shaft 41 is driven by any suitable constant speed driving means (not shown). A pair of mutually opposed cones 44, 44 is mounted on the shaft 41 and keyed thereto to be freely slideable thereon but enforcedly rotatable therewith. A similar pair of cones 45, 45 is mounted in like fashion on the shaft 42. A pair of levers 46, 46 is mounted on fixed pivots. The upper end (Fig. 3) of each lever 46 is pivotally secured to one of the cones 45 while its lower part is similarly attached to one of the cones 44 at an equal distance from its fulcrum. The lower end of each lever 46 carries a nut engaging with respectively oppositely threaded portions of the control shaft 43. The shaft 43 is drivable through a sprocket and chain drive 49 and a wheel and worm drive 50, 51 by a reversible electric motor 52. Connections to a suitable source of electric current (not shown) to run the motor in one direction or the other, are controlled by the switches 35 and 36 respectively as indicated in Fig. 4.

As described, overcorrection is obviated by the described coaction of the levers 37 and 38 with the serrated shoes 137 and 138 respectively, from which it results that the apparatus effects a partial correction, pauses momentarily, effects another partial correction, pauses again, and is completely inhibited to operate, substantially when satisfactory correction is completed.

The arrangement thus described will operate in a completely satisfactory manner in most instances, especially in connection with the manufacture and handling of multi-conductor electrical cables. In such instances the principal cause of changes in tension in the cable is the change in radius of the take-up spool or reel driven from the shaft 42 on which the cable is being wound, as layer after layer is wound on. Such change occurs usually somewhat abruptly when a layer is completed and the next turn of winding is laid on the just completed layer. If, however, some cause effects a very slow variation of tension, it may happen that, when an increment of speed

of the shaft 42 is made, the new speed and tension of the cable are such that conditions are just balanced with the contact edge of the switch lever in the bottom of one of the serrations of the shoe. As the lever 20 remains then in its new position, and also the plates 30 and 130 with both switches open, no new speed increment is effected and the whole process remains at the new tension level thus established differing slightly from the desired level.

In cases such as that last described, recourse may well be had to the amplified form shown in detail in Figs. 2, 3, 5 and 6. Here an upward extension 29 is attached rigidly to the middle of the plate 30 and carries a sheave 31. A cord 32 is attached at one end to an adjustable extension on the lever 20, passes over one member of a double guide sheave 33, around the sheave 31, around the other sheave 33, and over a guide sheave 34 to an extension 54 on the shaft 43 to which it is secured after being wound a number of times thereon. The plate 30 is not here tight on the shaft 21 as in Fig. 1, but is freely rotatable thereon and is held in the normal position shown in Fig. 2 between the spring 39 and the cord 32. The lever 130, as before, is movable against friction on its pivot 131.

Should the lever 20 move clockwise, it pulls the cord 32 and thus moves the plate 30 also clockwise with the results described above in connection with Fig. 1 where the plate turns in like manner with the shaft 21. The switch 36 is closed and the motor 52 drives the shaft 43, thus actuating the speed control to increase the speed of the output shaft 42. However, at the same time the cord 32 is unwound from the extension 54, allowing the spring 39 to return the plate 30 and thereby also the lever 130 to the normal position, opening the switch 36 and stopping the motor 52 to annul the actuation of the control.

The control exercised primarily by the serrated shoes 137 and 138 coacting with the levers 37 and 38 respectively, is such that an incorrect tension in the cable is corrected by intermittent step by step approximation, which may fall triflingly short of full correction but cannot become excessive. The control exercised by the cord 32 primarily is such that an incorrect tension in the cable is, in practise, corrected by a trifling overcorrection which is then corrected in turn, the consequent hunting being damped out rapidly. By combining the two controls, as in Fig. 2, each serves to make good the marginal errors of the other. While either is wholly satisfactory by itself in most cases in practise, there may be a few instances where the extreme delicacy of control afforded by the combination may be preferred.

The combination of switches actuatable by movement of the plate 30 under control of the cord 32 which in turn is controlled both by the lever 20 and by the extension 54, is not per se a part of the present invention, being a part of one phase of the present invention only in combination with the serrated shoe control. The cord control is described and claimed per se in copending application Serial No. 406,856, filed of even date herewith by Harry H. Merwin, and assigned to the same assignee as the present invention. Reference may be had to the said copending application for details of disclosure and description of the cord control not made wholly clear herein.

The embodiments of the present invention herein disclosed are illustrative and may be variously modified and departed from without departing

from the spirit and scope of the invention as pointed out in and limited only by the appended claims.

What is claimed is:

- 5 1. In a strand handling apparatus having means to advance a strand longitudinally and means adjustable to control the speed of advance of the strand, means responsive to variations of tension in the strand to adjust the speed control means, and means to cause the responsive means to actuate the speed control means intermittently to approximate a desired speed step by step.
- 10 2. In a strand handling apparatus having means to advance a strand longitudinally and means adjustable to control the speed of advance of the strand, means responsive to variations of tension in the strand to adjust the speed control means, and means to cause the responsive means to actuate speed control means intermittently, in combination with means actuatable by the control means to annul the actuation of the control means.
- 15 3. In a strand handling apparatus having means to advance a strand longitudinally in a free hanging catenary and including adjustable variable speed transmission means to control the speed of advance of the strand and thereby the tension in the strand, a member supported on the catenary of the strand and movable thereby in response to variations in the tension of the strand, means actuatable by the member to adjust the speed control means, and means interposed between the member and the adjusting means to cause the member to actuate the adjusting means intermittently to approximate a desired speed step by step.
- 20 4. In a strand handling apparatus having means to advance a strand longitudinally in a free hanging catenary and including adjustable variable speed transmission means to control the speed of advance of the strand and thereby the tension in the strand, a member supported on the catenary of the strand and movable thereby in response to variations in the tension of the strand, means actuatable by the member to adjust the speed control means, and means interposed between the member and the adjusting means to cause the member to actuate the adjusting means intermittently, in combination with means actuatable by the control means to annul the actuation of the control means.
- 25 5. In a strand handling apparatus having means to advance a strand longitudinally in a free hanging catenary and including adjustable variable speed transmission means to control the speed of advance of the strand and thereby the tension in the strand, a member supported on the catenary of the strand and movable thereby in response to variations in the tension of the strand, means actuatable by the member to adjust the speed control means, and means interposed between the member and the adjusting means to cause the member to actuate the adjusting means intermittently to approximate a desired speed step by step.
- 30 6. In a strand handling apparatus having means to advance a strand longitudinally in a free hanging catenary and including adjustable variable speed transmission means to control the speed of advance of the strand and thereby the tension in the strand, a member supported on the catenary of the strand and movable thereby in response to variations in the tension of the strand, electrical switch means to adjust the speed control means, a serrated shoe to coact with the switch means to actuate the same intermittently, and means actuatable by the member to cause relative motion of the switch means and the shoe to actuate the switch means.
- 35 7. In a strand handling apparatus having means to advance a strand longitudinally in a free hanging catenary and including adjustable variable speed transmission means to control the speed of advance of the strand and thereby the tension in the strand, a member supported on the catenary of the strand and movable thereby in response to variations in the tension of the strand, electrical switch means to adjust the speed control means, a serrated shoe to coact with the switch means to actuate the same intermittently, and means actuatable by the member to cause relative motion of the switch means and the shoe to actuate the switch means.
- 40 8. In a strand handling apparatus having means to advance a strand longitudinally in a free hanging catenary and including adjustable variable speed transmission means to control the speed of advance of the strand and thereby the tension in the strand, a member supported on the catenary of the strand and movable thereby in response to variations in the tension of the strand, electrical switch means to adjust the speed control means, a serrated shoe to coact with the switch means to actuate the same intermittently, and means actuatable by the member to cause relative motion of the switch means and the shoe to actuate the switch means.
- 45 9. In a strand handling apparatus having means to advance a strand longitudinally in a free hanging catenary and including adjustable variable speed transmission means to control the speed of advance of the strand and thereby the tension in the strand, a member supported on the catenary of the strand and movable thereby in response to variations in the tension of the strand, electrical switch means to adjust the speed control means, a serrated shoe to coact with the switch means to actuate the same intermittently, and means actuatable by the member to cause relative motion of the switch means and the shoe to actuate the switch means.
- 50 10. In a strand handling apparatus having means to advance a strand longitudinally in a free hanging catenary and including adjustable variable speed transmission means to control the speed of advance of the strand and thereby the tension in the strand, a member supported on the catenary of the strand and movable thereby in response to variations in the tension of the strand, electrical switch means to adjust the speed control means, a serrated shoe to coact with the switch means to actuate the same intermittently, and means actuatable by the member to cause relative motion of the switch means and the shoe to actuate the switch means.
- 55 11. In a strand handling apparatus having means to advance a strand longitudinally in a free hanging catenary and including adjustable variable speed transmission means to control the speed of advance of the strand and thereby the tension in the strand, a member supported on the catenary of the strand and movable thereby in response to variations in the tension of the strand, electrical switch means to adjust the speed control means, a serrated shoe to coact with the switch means to actuate the same intermittently, and means actuatable by the member to cause relative motion of the switch means and the shoe to actuate the switch means.
- 60 12. In a strand handling apparatus having means to advance a strand longitudinally in a free hanging catenary and including adjustable variable speed transmission means to control the speed of advance of the strand and thereby the tension in the strand, a member supported on the catenary of the strand and movable thereby in response to variations in the tension of the strand, electrical switch means to adjust the speed control means, a serrated shoe to coact with the switch means to actuate the same intermittently, and means actuatable by the member to cause relative motion of the switch means and the shoe to actuate the switch means.
- 65 13. In a strand handling apparatus having means to advance a strand longitudinally in a free hanging catenary and including adjustable variable speed transmission means to control the speed of advance of the strand and thereby the tension in the strand, a member supported on the catenary of the strand and movable thereby in response to variations in the tension of the strand, electrical switch means to adjust the speed control means, a serrated shoe to coact with the switch means to actuate the same intermittently, and means actuatable by the member to cause relative motion of the switch means and the shoe to actuate the switch means.
- 70 14. In a strand handling apparatus having means to advance a strand longitudinally in a free hanging catenary and including adjustable variable speed transmission means to control the speed of advance of the strand and thereby the tension in the strand, a member supported on the catenary of the strand and movable thereby in response to variations in the tension of the strand, electrical switch means to adjust the speed control means, a serrated shoe to coact with the switch means to actuate the same intermittently, and means actuatable by the member to cause relative motion of the switch means and the shoe to actuate the switch means.

speed control means, a serrated shoe to coact with the switch means to actuate the same intermittently, and means actuatable by the member to cause relative motion of the switch means and the shoe to actuate the switch means, in combination with means actuatable by the control means to annul the actuation of the control means.

7. In a strand handling apparatus having means to advance a strand longitudinally in a free hanging catenary and including adjustable variable speed transmission means to control the speed of advance of the strand and thereby the tension in the strand, a member supported on the catenary of the strand and movable thereby in response to variations in the tension of the strand, a lever movable by the member, electrical switch means mounted to be movable by the lever and actuatable to adjust the speed control means, and a serrated shoe mounted to be movable by the lever to have motion relative to

the switch means to actuate the switch means intermittently.

8. In a strand handling apparatus having means to advance a strand longitudinally in a free hanging catenary and including adjustable variable speed transmission means to control the speed of advance of the strand and thereby the tension in the strand, a member supported on the catenary of the strand and movable thereby in response to variations in the tension of the strand, a lever movable by the member, electrical switch means mounted to be movable by the lever and actuatable to adjust the speed control means, and a serrated shoe mounted to be movable by the lever to have motion relative to the switch means to actuate the switch means intermittently, in combination with means actuatable by the control means to annul the actuation of the control means.

20

WALDEMAR C. EWALDSON.
